UNITED STATES PATENT OFFICE.

ANTON HOERSCH, OF MENASHA, WISCONSIN.

STORM-WINDOW VENTILATOR.

1,105,784.

Specification of Letters Patent. Patented Aug. 4, 1914.

Application filed April 5, 1913. Serial No. 759,170.

To all whom it may concern:

Be it known that I, ANTON HOERSCH, a citizen of the United States, residing at Menasha, in the county of Winnebago and State of Wisconsin, have invented a new and useful Storm-Window Ventilator, of which the following is a specification.

My invention is for use in a dwelling house or other building, and is adapted for use upon a storm window sash in connection with the upper sash of an inside window of a room, for the purpose of providing ventilation thereof, and at the same time adapting said inside window for use as a ventilator, when the storm window sash has been removed during warm weather, the lowering of the sash of the inside window being entirely under the control of persons inside of the room and cannot be interfered with by persons outside thereof, and it consists of a supplemental ventilating sash, fitted into an opening above the glass within the usual storm sash upon the outside of a window, and is hinged from its upper rail for swinging outward, there being mechanism at each end of said supplemental sash connecting with the outside of the inside window sash for swinging said supplemental sash open and for closing the same, as said inside window sash is lowered for ventilating the room, or raised for closing the window, said upper sash of the inside window being provided with a screw for opening and closing it, the several parts being shown in the accompanying drawing, in which,—

Figure 1 is an elevation in which the upper portion of an inside window and its casing is shown, the upper sash being lowered by means of a screw suspended from the soffit of the window lintel, it showing above the lowered sash the supplemental ventilating sash swung partly open, and some of the mechanism for operating it. Fig. 2 is a vertical section upon the line *a*, *a*, of Fig. 1, as it appears in looking toward the left from said line. Fig. 3 is an elevation in which the upper portion of the storm and the outside casing of the usual window are shown, with the supplemental ventilating sash hinged to the upper rail of the storm sash, and showing also, part of its operating mechanism. Fig. 4 is an elevation showing one corner of the window outside of the building, with the storm sash removed, a part of the operating mecha-

nism being secured to the upper end of said inside sash. The other figures are details, Fig. 5 being an end view of a nut which is secured to the upper rail of the inside upper sash. Fig. 6, is a plan of a socket for receiving the upper end of the sash operating screw. Fig. 7 is a side elevation of a rod holder for attachment to the lower corners of the supplemental sash. Fig. 8 is a plan of an angle lever iron which is pivoted between ears of a plate which is secured to the upper corners of the supplemental sash. Fig. 9 is an edge view of an open ended loop which is used in the operating mechanism. Fig. 10 is a plan of said loop. Fig. 11 is an edge view of a closed loop in which the loop 10 is arranged to slide. Fig. 12 is a plan of Fig. 11.

Similar numerals and letters indicate like parts in the several views.

1, indicates the inside window casing and 1^a, the outside casing; 2, the upper sash of the inside window; 3, the lower sash; 4, the top rail of the upper sash; 5, the side rails; 6, the glass; 7, the soffit of the window lintel; 7^a, sash stops; 8, a socket secured to the soffit into which the end of the screw 9 enters and is held from lengthwise movement; 10, a nut fitted to said screw; 11, a groove around the upper end of the screw rod for fitting the bore 12 in the socket; 13, a collar secured upon the upper end of the screw and forming one end of the groove 11. By turning the screw by means of the element 9^a, which element may be a hand wheel, the sash 2 can be lowered any amount within the limits of the length of the screw, and a ventilating means provided of ample width for night use, and the screw being properly limited in its length, the opening will be safe from the entrance of outsiders, and the opening and closing of the sash by means of the screw provides an easy and safe method of operating the window at all times of the year, either with or without the storm sash being used.

14, indicates a storm sash which may extend the entire length and width of the outside opening for the window. It consists of 15 the usual top rail 15, a bottom rail, (not shown,) any desired number of cross rails 16, intermediate the end rails, a supplemental cross rail 17, and side rails 18, the supplemental rail being spaced from the top rail the desired distance for the ventilating sash. The top rail 15, cross rail 17, and side

rails between rails 15 and 17, are provided with rabbets 19 for receiving the rabbeted rail ventilating sash 20, which is hinged to the storm sash top rail with butts 21. A 5 plate 22, provided with upstanding ears 23, is secured with screws or otherwise to each vertical rail of the sash 14, in each of which plates an angular lever is pivoted upon a pin 24, one arm of each lever being a round 10 rod 25, which extends downward along a side rail of the sash and is fitted to slide easily through a hole 26 in the holder plate 27, and the other arm 28, is flattened, passed through a suitable mortise 22^a, through the 15 plate and sash, and is connected to an open ended loop 29 by means of a pin or bolt 30, each loop 29 engaging around the closed loop 31 of the plate 32, which plate is secured to the outside of the inside window sash 2. 20 The pin 30, may be a small cotter pin or a bolt and nut. The loop 31 is of some length, according to the distance of the vertical movement of the sash 2, so that the sash being at the upward limit of its movement, 25 it will be lowered about one half the distance it is arranged to be lowered, before the upper end of its loop 31, will engage with the lower end of the loop 29, and pull downward upon the arm 28 for opening the ventilating sash 20. The loops 29 and 31, should 30 be of such lengths and be so connected with the inside and ventilating sash, that when the inside sash is closed, the lower ends of the loops 29, will be engaged inside of the 35 lower ends of the loops 31, and hold the sash 20, closed. The round rod ends 25 of the angle levers, as the pull is made upon the ends 28, are caused to slide through the holes 26 in the plates 27, as the ventilating 40 sash is swung upon its hinges.

It will be evident that with window sash provided with balancing weights, means for operating the sash are provided, so that the screw lowering means is not essential for the 45 successful operation of the ventilating sash,

but that in dispensing with it, the safety element from outside interference will be sacrificed. It will also be seen that other sash raising means besides the screw can be successfully applied to the sash for operating 50 the ventilating sash. It may be further observed that the storm sash need only come up as high as the ventilating sash, and said ventilating sash be hinged directly to the window lintel. For convenience in applying 55 the ventilating sash, the method shown is preferable.

Having described my invention, what I claim and desire to secure by Letters Patent, is,—

A window ventilator, comprising a vertically sliding window sash, a storm sash secured in the window opening outside of said sliding sash, a supplemental ventilating sash hinged upon its upper horizontal rail for 60 swinging outwardly, and adapted for filling any space left unfilled by the storm window sash under the window lintel, an angular bent lever pivoted to swing a limited amount within a suitable holder which is secured to 65 the outside of the supplemental sash side rails, a rod extending downward from near the pivotal point of each angular lever, a holder secured near each lower end of the supplemental sash side rails through a hole 70 in which one of said rods slide, an arm extending inward through the supplemental sash rails from the angle of each lever, a closed loop secured upon the outside of each side rail of the inside sash near its upper 75 end, and an open ended loop connected with each closed loop aforesaid, and with the inward extending arm of each angular lever aforesaid by means of a suitable removable pin or bolt.

ANTON HOERSCH.
